John Sealy Jr.

United States Patent Office.

JOHN SEALY, JR., OF NEWARK, NEW JERSEY.

Design No. 3,650, dated August 31, 1869.

DESIGN FOR AN ORNAMENT FOR A CHILD'S HAT.

The Schedule referred to in these Letters Patent and making part of the same.

To all whom it may concern:

Be it known that I, JOHN SEALY, of the city of Newark, in the county of Essex, and State of New Jersey, have produced an original Design for Style and Ornament for a Child's Hat, of which the following, taken in connection with the accompanying drawings, is a full, clear, and exact description.

A cord of various colors, or of black intertwined, is, from a fringed button in front, passed along the side and knotted, as shown in the drawing, having tassels at the ends hanging over the side of the brim, and a button is placed on the centre of the crown.

This ornament, combined with the contour of the hat, which is indescribable, and can only be taken by the eye, constitutes the style of the whole.

What I claim as my production, and desire to secure by Letters Patent, is—

The design, in style and ornamentation, of the hat as herein set forth.

JOHN SEALY, JR.
